UNITED STATES PATENT OFFICE.

EDMUND S. G. REES, OF WOLVERHAMPTON, ENGLAND.

PROPELLION AND STEERING OF SHIPS.

1,344,518.

Specification of Letters Patent. Patented June 22, 1920.

Application filed March 5, 1919. Serial No. 280,741.

To all whom it may concern:

Be it known that I, EDMUND SCOTT GUSTAVE REES, a subject of the King of Great Britain, residing in Wolverhampton, England, have invented certain new and useful Improvements in the Propulsion and Steering of Ships, of which the following is a specification.

This invention relates to the propulsion 10 and steering or maneuvering of ships driven by screw propellers.

The principle involved is disclosed to a certain extent in the British patent specification No. 9435 of 1908 and as in the invention described in that specification, the present invention seeks, *inter alia* to realize the condition of maximum efficiency laid down by Macquorn Rankine that, *ceteris paribus*, that propeller is most efficient which drives 20 the greatest weight of fluid astern at the slowest speed.

According to the present invention the maneuvering of such ships is effected by means of one or more fixed tubes or ducts 25 open at both ends to the surrounding water into or through which ducts the water set in motion by the propeller passes and from which its ejection is controlled by means of one or more pivoted vanes or pallets or pairs 30 of pallets so arranged that the whole of the water set in motion by the propeller may be allowed to pass rearwardly through and out of such tubes or ducts, or may be deflected so as to be ejected therefrom toward 35 port or starboard or in a forward direction or directions, or part of the water may be deflected forwardly while the remainder passes sternward or to port or starboard, thereby enabling the ship to be maneuvered 40 solely by means of the tube or duct and controlling pallets without reversal of engine or propeller and if desired without any alteration whatever of engine or propeller speed. Such tubes or ducts will therefore 45 be referred to hereinafter as maneuvering tubes and the stream of water set in motion by the propeller as the flume.

The invention may take a considerable 50 variety of forms, some of which are embodied in the accompanying drawings with reference to which the invention is described in greater detail, but in its simplest form the invention consists of a short fixed rearwardly flaring maneuvering tube, the forward end of which encircles the propeller or

is immediately astern thereof, while the rear end is provided with means for controlling the direction of flow of the flume within and from the tube, as for example a pair of vertically pivoted control vanes or pallets 60 which can be moved in opposite senses so as to close the rear end of the tube completely or partially, or, in the same sense, to deflect the flume laterally to either side, or to do both in part.

In the drawings Figures 1 to 6 are various views showing one embodiment of the invention, Fig. 1 being a longitudinal sectional elevation, Fig. 2 a sectional plan and Fig. 3 an end elevation, while Figs. 4 to 6 70 are part plans showing various positions of the control pallets.

Figs. 7, 8 and 9 are, respectively, a side elevation, plan view and rear elevation partly in section, illustrating the application of the invention to a ship fitted with 75 twin screws.

Figs. 10 to 14 are views showing a modified construction of control pallets, Fig. 10 being a longitudinal sectional view, Figs. 80 11, 12 and 13 part plan views showing various positions of the control pallets, and Fig. 14 an end elevation.

Figs. 15 and 16 are, respectively, a side elevation and a plan view of a form of gear 85 for operating the control pallets.

As shown in these drawings, *a* represents the screw propeller, coaxially arranged with which is a maneuvering tube or duct *b* of horizontally flattened or elliptical section, 90 the side walls of which moreover are chamfered or cut away at the forward end as shown at *b*¹, to give free access of water to the propeller and, at the rear end, as shown at *b*², to accommodate and permit the required site movement of the control elements.

The forward end of the duct *b* embraces the propeller, in the rear of which the duct expands or flares to the rearward opening which is controlled by a pair of flat plates 100 or pallets *c*, *d* carried on brackets *c*¹, *d*¹ which are pivoted vertically upon a central axis *e*.

In Figs. 1, 2 and 3 the control pallets are shown in the position for maximum headway, in which position the flume is allowed to pass freely through the duct *b*.

In Fig. 4 the control pallets are shown closed on each other at their rear edges so as to deflect the flume in a forward direction.

tion. This position of the pallets is that for maximum sternway.

In Fig. 5 the control pallets are shown in an intermediate position, in which the forward edges of the pallets abut against the chamfered rear edges of the side walls and part of the flume is allowed to pass between the rearward edges of the pallets while the remainder is deflected forwardly by the control pallets through the maneuvering tube or duct. In one such intermediate position of the pallets the vessel will remain stationary while in other intermediate positions the ship will go ahead or astern as the case may be at various speeds. The position of the control pallets shown in Fig. 6 is such as to direct the flume toward the left, thus turning the ship to port.

It will be noted that the maneuvering tube or duct *b*, besides being flattened and cut away laterally at the front and rear ends also flares in both directions, that is forwardly at the front end around the propeller, and rearwardly throughout the remainder of its length to the rear opening. This construction augments the flume more than a parallel sided tube would do and reduces the average speed of ejection, thereby increasing the efficiency of propulsion.

In the twin screw construction of Figs. 7, 8 and 9 each propeller is associated with a separate maneuvering tube *b*, the inner sides of these two tubes being parallel, while the outer sides are shaped to give the desired augmenter action.

These tubes, as shown in Fig. 9, are of oval or egg-shaped section and are cut away on the outer side at their forward ends *b*', where, as shown on these drawings, they embrace the propeller, their rear ends being each fitted with a flat plate or control pallet *c* centrally pivoted about a vertical axis and the ducts themselves are connected at top and bottom by two curved plates *f* which form a common inclosing oval duct. It will be seen that with the control pallets *c* in the position shown in Figs. 7, 8 and 9 of the drawings the flumes are deflected forwardly within the space bounded by the ducts *b* and inclosing plates *f* in a direction parallel with the fore and aft axis of the ship, that is in the direction which gives the maximum stern-way speed to the ship.

In the modified construction of pallets shown in Figs. 10 to 14 which may be used in lieu of the plain plates previously described, pairs of twin plates, disposed in louver-fashion are employed for controlling the end of the maneuvering tube *b*, the space or passage *n* between the twin plates constituting a nozzle which is directable with the movement of the pallets. The nozzles can be made of such a size or area as to take the place of the gap or nozzle formed

by the outer edges of the control pallets 65 and the rear edges of the control duct in the closed position of the pallets as in Fig. 4.

Figs. 15 and 16 are respectively a longitudinal elevation and a plan view of a form 70 of gear for operating the control pallets.

The tiller *g* which may be operated by hand or by mechanical power (not shown in the drawings) is adapted to turn the control pallets *c*, which in this case are shown 75 mounted on separate vertical pivots, in the same sense through gear wheels *h*, *j*, *h*', *j*'; and a worm gear *k* actuated by a hand wheel *k*', mounted on the tiller is arranged to turn the control pallets *c* in opposite senses 80 through bevel gearing *l*.

The augmenter effect of the maneuvering tube may be amplified by the use of one or more coaxial fixed tubes or ducts leading from one to the other from the propeller to 85 the maneuvering tube, that is to the tube fitted with the control pallet or pallets.

Such an additional augmenter tube is shown by way of example in Figs. 15 and 16. As shown, the additional tube *m* is 90 cylindrical and of a diameter equal to the vertical dimension of the maneuvering tube *b*, leaving lateral gaps *o* between the tubes *n* and the side walls of the flattened maneuvering tube *b*.

It will be understood that such additional augmenter tube or tubes may be parallel sided, whether flattened or otherwise, or may be flaring in one or both directions, or cut away laterally at their forward end as 100 may be the case with the maneuvering tube itself.

With such an auxiliary augmenter tube or tubes interposed between the propeller and the maneuvering duct, not only is the mass 105 of water set in sternward motion increased and its average velocity reduced when the vessel is going ahead, but additional forwardly directed outlets are provided for the ejection of the water when the control pallets are set for stopping or going astern or for making headway at reduced speed independently of the engines. A similar result may be obtained by providing the maneuvering tube with lateral gills or forwardly directed openings at one or more points along its length.

Further, the maneuvering tube and also any other tube used in association therewith may be divided throughout the whole or 120 part of its or their length by a web or webs in any suitable longitudinal plane or planes.

When the invention is applied to the submersion or emersion of submarines the control vanes or pallets are horizontal instead of vertical and the maneuvering tube and other tubes which may be used in association therewith are similarly orientated.

When it is desired to use the same means for horizontal maneuvering and for submersion, the maneuvering tube or duct, or an end section of the same especially 5 mounted for the purpose, is made rotatable about its axis and securable in the desired position by suitable means.

Having thus described the nature of the 10 said invention and the best means I know of carrying the same into practical effect, I claim:—

1. In ships propelled by screw propellers, the combination with each propeller of a fixed maneuvering tube or duct open at each 15 end to the surrounding water and expanding in rear of the propeller to the rear opening and means located at the rear end of the duct for controlling the direction of flow within and from the tube of the streams or 20 flume set in motion by the propeller.

2. In ships propelled by screw propellers, the combination with each propeller of a fixed maneuvering tube or duct open at each end to the surrounding water and expanding 25 in rear of the propeller to the rear opening, said tube being of flattened or elliptical section with its major dimension horizontal, and means located at the rear end of the duct for controlling the direction of flow

within and from the tube of the streams or 30 flume set in motion by the propeller.

3. In ships propelled by screw propellers, the combination with each propeller of a fixed maneuvering tube or duct open at each end to the surrounding water and expanding 35 in rear of the propeller to the rear opening, said tube having its side walls chamfered at the rear end, and vertically pivoted pallets mounted at the rear end of said tube and adapted in one position to 40 form a continuation of the chamfered side walls of the tube.

4. In ships propelled by screw propellers, the combination with each propeller of a fixed maneuvering tube or duct open at 45 both ends to the surrounding water and expanding in rear of the propeller to the rear opening, vertically pivoted pallets mounted at the rear end of said tube, and openings or nozzles formed in said pallets and 50 adapted, when the rear edges of the pallets are closed on each other, to eject the water forwardly from the tube and external thereto.

In testimony whereof I have signed my 55 name to this specification.

EDMUND S. G. REES.
